GRAVITY FLOW SINTERING MACHINE

Walter Kelsey, New York, N. Y.

Application March 22, 1947, Serial No. 736,487

8 Claims. (Cl. 266—20)

1

This invention relates to sintering machines. The invention contemplates a gravity flow sintering machine, the function of which is to sinter ores; in general, to sinter or agglomerate any materials that will sinter, and for any use.

In the steel industry alone this machine is valuable in making usable, in the blast furnace for instance, low grade and crude iron ores, and waste from steel mills and shops.

The sintering machines at present in use are elaborate and costly to build and limited in their scope of use. The present invention is simple in design and construction, less costly and has a wide scope of use, and the operation is continuous. The stock supplied to the machine, is, in general, a mixture of the material to be sintered and a fuel, as well known.

The invention consists more particularly of an inclined sintering pass, in which the flow of stock and sinter is regulated in consonance with the sintering action, with its body portion subjected to an induced flow of air, and having its upper end provided with a feeding chute. At the lower end of the feeding chute, the stock is ignited continuously and brought to incandescence, by action of a flame on the stock, which ignited stock is transposed to enable the transposed incandescent stock to sinter in the sintering pass under the action of the induced air flow. The fire line is disposed between the stock and the sinter, and the sintered stock is subjected to controlling rollers or crushing means operating in consonance with the amount of stock sintered. The action throughout is continuous.

The invention will be further described, embodiments thereof shown in the drawings, and the invention will be finally pointed out in the claims.

In the accompanying drawings,

Fig. 1 is a vertical sectional side view taken on line 1—1 of Fig. 3;

Fig. 2 is a diagrammatic partial view of two suction chambers, one for sintering and one for cooling;

Fig. 3 is an inclined section taken on line 3—3 of Fig. 1;

Fig. 4 is an inclined section taken on line 4—4 of Fig. 1;

Fig. 5 is an inclined section taken on line 5—5 of Fig. 1;

Fig. 6 is a vertical section taken on line 6—6 of Fig. 1;

Fig. 7 is a side view of the air lock plates;

Fig. 8 is a partial front view of the air lock plates;

2

Fig. 9 is a diagrammatical view of the operation of certain of the essential features of the invention, and

Figs. 10 and 11 are diagrammatical partial views of different positions of the fire line.

Similar characters of reference indicate corresponding parts throughout the various views.

Referring to the drawings, the inclosed feeding chute 10 is either vertical or sloping in such a manner that there is a gravity flow of the stock. The length of the feeding chute 10 between a gate 11 and an ignition chamber 17 is such that there is no appreciable loss of air suction through the stock held in the feeding chute 10.

As a means of preventing excessive compacting in the feeding chute having a stock guide, sections 13 forming pockets 13a filled with stock are provided in the feeding chute. The stock flowing off of the stock body held in the pockets 13a moves with less force than if the stock had an unimpeded flow. Also each pocket takes practically all of the weight of the stock within the chute vertically above the pocket.

To prevent the lower layer or part of stock in the bottom of the feeding chute 10 from flowing ahead of the upper layer or part of stock in the chute, a row of chains 14 is hung in the feeding chute. These chains 14 are so hung that they will lay in the lower layer of flowing stock or in the bottom 10a of the feeding chute and furnish enough resistance to retard the flow of this lower layer of stock.

At the bottom 12 of the feeding chute 10 the top surface of the stock is not restrained and takes its natural slope as it passes below an ignitor or ignition flame 17a either in the open or in an ignition chamber 17, and then as an ignited stock or newly made sinter 52 the top surface of which 53 (see Fig. 9) passes below an air cooling intake 19 with a flow adjusting damper 19a, and thence below the plunger 21 or other transposing means.

The ignition chamber 17 is so made as to burn the fuel used to a flame. The flame is impinged upon the exposed surface of the stock descending in the feeding chute throughout its width so as to properly ignite the stock while it passes below the chamber 17. Air suction aids to draw the flame to the surface of the stock. The intensity of the flame, the width of the ignition chamber, the amount and rate of flow of the stock, and the intensity of the air suction, are individually adjusted to give proper ignition to the stock. One side of the ignition chamber 17 forms a barrier 20 between the ignition chamber and an air intake 19, and the bottom of the bar-

rier is adjustable by a slide 20a clearing the sintering stock as it flows underneath.

Instead of the ignition chamber an open flame may be used impinging on the stock, and disposed above the barrier 20 with its slide 20a.

The air blast intake 19 is made to force a blast of air directly upon the hot surface of the ignited stock or sinter 52 with the object of cooling its surface 53 under retention of a fire line 51, so it will not adhere to a flow-directing plunger or other transposing means, about to be described.

At the top of the sintering pass 15, the flow of the ignited stock or sinter is transposed in position, and that ignited stock or sinter which was the front layer located above the bulk of the moving stock in the feeding chute now becomes the front layer located below the bulk of the moving stock in the sintering pass 15. For this purpose, a power driven plunger 21 or other power driven device is placed in the front side, at the top of the sintering pass 15. This plunger 21 has an inclined portion 55 (see Fig. 9) to facilitate the transposal of the sinter and fire line, and forces the newly made sinter with its fire line or the adjacent ignited stock, down along the front side of the sintering pass 15 at such a speed as to match the flow of the rest of the ignited stock so as not to break the continuity of the ignited stock or sinter. The inclined side of the plunger pushes the fire line 51 into an inclined position 51a, as shown in Figs. 10 and 11. Then the plunger withdraws. The bulk of the stock pushes the inclined fire line 51a towards the front side of the sintering pass into the position 51b. While the plunger withdraws, the initial fire line 51 keeps on moving in the same direction as when formed. When the end reaches the front side of the sintering pass, the next movement of the plunger moves it to the inclined position 51a. Thence the sinter and ignited stock and unburned stock continues to flow or slide down on the front side of the inclined sintering pass. Upon the induced air acting upon the fire line and superposed stock, the fire line 60 is drawn along and sinters the superposed stock. As the stock and the sinter flows down the sintering pass 15, the fire line 60 takes a mean diagonal position, until the superposed stock is entirely sintered. The unburned stock is restrained by the back side 15c of the sintering pass for a suitable length.

To prevent excessive compacting at the point of transposal of flow, the bottom of the feeding chute is made to project as shown at 22 beyond the lower face of the back side 15c. This will leave a portion of stock without any direct vertical load with only the side pressure to force this portion of the stock back against the back side. This gives a release for the side pressure developed by the corner plunger 21 or other turning device. In the embodiment, the plunger 21 has a link 21a pivoted to a crank arm 21b operated by a shaft 21c.

The sinter and stock in the sintering pass 15 is traversed by an air flow for a space equal to the length of the air chamber 29. The induced air flows from the front of the air chamber 29 through the perforations 15b in the wall 15a and transversely through the entire width of the stock to a suction chamber 30 enclosed by a back side 30a of the casing forming the suction chamber 30. As the stock flows down, the air draws the fire toward the suction chamber 30. The air is heated by the sinter, thus aiding in the combustion of the fuel in the stock and also acts

to cool the sinter. The speed of stock flow and amount of air or draft is so adjusted that the fire will burn entirely through the stock. Sintering, which begins at the ignition flame, is completed at a point 0 below the lower end of the back side 15c, at which place the stock surface is not restrained, and the top surface of the stock flows free at its natural slope. In front of the fire line 60 and below the point 0 where the fire has burned through, all the stock has become rigid sinter and its plastic character having been lost by the cooling, it will flow or slide down to controlling crushing rollers 24 and 25, and when crushed to a conveyor 26. The cooled and hardened sinter is gripped and handled by the power driven controlling rollers 24 and 25.

Over the free surface of the sinter below the suction chamber, air locks 23 are arranged. The length of the sinter pass from the bottom of the suction chamber to below the lowest air lock 23 is such that there is no appreciable loss or air suction through the sinter or stock held in the sintering pass 15.

The controlling and crushing rollers 24 and 25 are driven at such speed as to give the desired flow of stock in the sintering pass. Known means (not shown) are provided for changing the speed of the rollers 24 and 25. The crushed rigid sinter falls on the pan conveyor 26 which is driven at such speed that the sinter on the conveyor just clears or is free of the rollers. The conveyor 26 discharges the sinter into the screen 27 or processing room. The pan conveyor 26 is the preferred form, but other forms of conveyor may be used. The control and crushing means may be modified as to the means shown, but the control feature is important.

The air flow induced from the ignition chamber 17 by the suction chamber 30, and from the air chamber 29 by the suction chamber 30, is produced by a suction fan 34. The front side of the air chamber 29 is indicated by 29a. The front side 15a is perforated by holes 15b, the location and number of which is established by the requirements of sintering and the demand for air along the front side 15a. The bottom 10a of the lower part of the feeding chute 10 and the back side 15c of the sintering pass are also perforated with holes 15d, the location size and number of which is established by the amount of air which is to be allowed to pass.

An equalizing damper 35 is placed in the suction chamber 30. This damper 35 extends from end to end of the chamber 30 and fits over the back side 15c of the sintering pass to equalize the air flow, or give the suction desired, to bring the fire to the surface of the stock at the desired location 0 and to allow ample air for the cooling of the sinter. This damper 35 is arranged to be raised or lowered by known regulating devices 35a at either end to equalize air flow and to compensate for any eccentric end draft from the suction duct. Thus, this equalizing damper 35 provides means to bring the fire to the surface of the stock at the desired location 0.

The air lock 23 which is placed where the sinter leaves the suction chamber, consists of flat plates 37 suspended close together on a shaft 38 (Figs. 7 and 8). The bottoms of these heavy plates rest on and take the irregularities of the top of the sinter as it passes underneath. There is very little open space for the passage of air. One lock or more locks may be used, in series if necessary. In Fig. 2 is shown a separate suction chamber 30b

controlling the air lock arrangement, having a fan 34a in the outlet channel casing 15e.

When the gravity flow sintering machine is in operation, the feeding chute and sintering pass is full of stock and sinter. The stock from the supply at the gate and that in the machine puts a pressure on the contents of the machine which acts to force the stock and sinter down through the machine. This force, which is gravity acting on the materials, forces the stock and sinter to follow downward through the machine as sinter is discharged from the bottom of the sintering pass by the controlling and crushing rollers. This discharging from the bottom of the rigid sinter acts to reduce the compacting of the stock in the upper part of the sintering pass.

With the exception of the retarding pocket or pockets 13a there is no place in the machine for the collection or holding of stock. The machine is self-cleaning and clearing when operated for this purpose.

This machine may be so built as to be practically dust proof. The inclosure which can include the screen or processing room may have the dust laden air drawn into the air chamber through an air intake 39 adjusted by the regulator 39a. The air and gases resulting from the sintering process may be run through a dust collector either before or after the suction fan. The air intakes 19 and 39 to the air chamber 29 are so adjusted that the one 19 at the ignition chamber will have sufficient air passing to give desired cooling blast for the sinter.

Hot sinter will be in contact with the plunger 21, the top of the front side and with parts of the ends 61 of the sintering pass. The metal at these places including the plungers and supporting parts thereof is heat resisting and a metal to which the hot sinter will not readily adhere.

The operation is as follows:

To start the gravity flow sintering machine, the stock supply gate 11 is opened filling the entire machine with stock. If the machinery is not running, the machine will stand full of stock as the conveyor 26 at the bottom is so placed that the stock will take its natural slope below the rollers and be held on the conveyor 26 as indicated by lines 24a and 25a. When the machine begins to operate, the conveyor will carry the stock away at a velocity to give the stock the desired speed for the downward flow in the sintering pass. The suction fan 34 is now started and the ignition flame 17a is now ignited. Sinter obtained by this flame ignition and maintained by the air suction will follow the stock, as indicated by the fire line 60, through the sintering pass. Any stock going through the machine without being converted to sinter is separated from the sinter and is returned to the stock processing line. Partial loss of fire or ignition does not stop the process as the stock and sinter both pass through the machine at the same velocity, thus allowing a pick up in ignition. However, the machinery must run and the ignition flame must be maintained to produce a continuous output of sinter.

In Fig. 9 is shown diagrammatically the incoming flow of the stock, into the gravity acting inclined sintering pass 15.

When the stock 50 is ignited by the action of the ignitor 17a upon the descending stock 50, a fire line 51 is formed contiguous to which the sintered stock 52 is formed, which increases in depth due to the action of the incandescence. When the flame 17a strikes the stock, or is impinged against the stock, the incandescence is from the flame ad-

jacent surface inwardly into the stock. When the sintering material and stock is subjected to an induced air flow, as through wall 10a, the desideratum is to pull the incandescence into the unsintered stock.

The surface 53 of this incandescent portion 52 is cooled by an air flow 54 (Figs. 9, 10 and 11). The lower end of this cooled surface 53 is subjected to the action of a plunger 21. This plunger changes the flow of the sintered stock 52. It acts as a sinter flow director. The surface of the sinter stock 52 corresponding to the inclined face of the plunger 21, is indicated by 53a, and this surface 53a, is diverted by the plunger 21, which directs the firing line 51 to the position 51a, so as to be at an angle to its original direction. Upon the withdrawal of the plunger 21, the firing line 51a is pressed by the downwardly moving stock to the position 51b, and initiates the firing line 60.

In Fig. 10, the plunger 21 engages the surface 53 forcing the sinter and incandescent layer 52 (see Fig. 9) and stock downward along the front side of the sintering pass to the position between 52A—52B with the cooled surface 53a in contact with the plunger 21 at the low position of plunger 21. As the plunger 21 returns to its high position, the sinter and incandescent layer between 52A—52B is forced down against the front side 15a by the pressure of the stock 50 in the feeding chute. This cycle is repeated with each stroke of the plunger 21 and places the cooled surface of the sinter against the front side 15a of the sintering pass 15 with the incandescent layer and stock above instead of below the sinter. Due to the induced air flow and descent of the stock, the incandescent layer or fire line then takes an inclined line 69.

In Fig. 9 is shown the initial position of the flow of the ignited stock down to the front side 15a. In Fig. 10 the down position of the plunger 21 is shown whereby the cooled surface sinter 53a and the incandescent line 51 is diverted to the angular position shown. On the return of the plunger, there is a space left. The pressure of the stock then forces the sinter and fire line 51 downwards against the front side 15a, as shown in Fig. 11. The action of the plunger is intermittently continuous and its next descent then again acts on the material as shown in Fig. 9, which material has in the meantime entered the space referred to and then is subjected to the action shown in Fig. 11.

Thus the machine takes the prepared stock from a supply, passes this stock by gravity flow through an inclosed feeding chute so that the stock passes an ignition flame and continues the gravity flow, the feeding chute above and the air locks below forming air throttling portions, one at each end of the sintering pass acted upon by the induced air.

From the foregoing it is seen that the invention includes a gravity flow sintering machine, in which the prepared stock for the same flows by gravity through a substantially vertical inclosed feeding chute blocking off the air flow, with the stock feeding into an inclined sintering pass. The body of the stock prior to its passage into the sintering pass, is continuously acted upon by a flame to ignite a locally exposed upper surface of the stock. This ignited and burning surface of stock is turned by turning means while in a plastic and burning condition to become the hard lower surface of the body of stock, from which a fire line is formed dividing the stock and sinter 75 in its flow or sliding through the sintering pass,

The body of sinter and stock divided by the fire line by being traversed transversely by air, enables the combustion to be continuously carried on, and on the completion thereof, to be cooled, as these materials flow down the sintering pass, producing a practically rigid block of sinter, furnishing a blocking off of air flow at its lower end. This block of sinter is engaged by the controlling and crushing means and is discharged by the same from the sintering pass. The action is continuous from the feeding of the stock to the crushing of the sinter, with the crushing carried on relatively to the amount of sinter being produced, or conversely stated, the crushing is regulated to bring about a co-related amount of sintering.

It will also be noted that in the feeding chute the flame action or ignition of the stock at the ignition chamber is with flame above the stock and the fire line drawn downwards by the air suction, but in the sintering pass the ignited stock is below the stock mass and the fire line is drawn upwardly, these separate actions taking place at about 90° to each other.

It will be noted that the front side 15a with its openings 15b extends below the lower end of the backside 15c with its openings 15d. The upper surface of the stock below the lower end of the back side 15c is free and unrestrained, but is subject to the suction action of the suction chamber 30. When the stock has been sintered, the upper surface of the sinter is free and unrestrained, and the upper part of the sinter in the sintering pass is subject to the suction chamber 30. When a second suction chamber is used as shown by Fig. 2, air exhaust is taking place by fan 34a, for instance, the upper air lock 23 acts as a barrier or separating means between the two suction chambers. This air lock acts as an air choke, or provides an air choking action. The fan 34a sucks air from the lower openings 15b of the front side 15a, and the sinter is thereby cooled.

The feed chute as described prevents air from being sucked in, and thus also acts as an air choke, or provides an air choke action. Thus, between these upper and lower air chokes, the sintering and some part of the cooling take place.

To operate the machine, the shaft of the crusher 25, transmits power to the shaft of the roller 24, and to the drive shaft of the conveyor 26, and to the drive shaft 21c of the plunger, in order to have these parts act in unison, suitable linkage being utilized.

I have described several forms of my invention, but obviously various changes may be made in the details disclosed without departing from the spirit of the invention as set out in the following claims.

I claim:

1. In a sintering machine, an enclosed stock feeding chute, vertically disposed, including a vertical stock guide having a vertical wall and an adjacent horizontal wall, said horizontal wall forming with its adjacent vertical wall a flow retarding pocket at the lower end of the first stock guide, a second vertical stock guide, having a vertical wall and an adjacent horizontal wall, said horizontal wall forming with its adjacent vertical wall a flow retarding pocket at the lower end of the second stock guide, disposed laterally out of vertical alignment with the first stock guide for directing the stock at an angular direction to the vertical flow of the first stock guide, an inclined wall between the pockets for

5 directing the stock flow at an angular direction to the vertical flow in the second stock guide, an ignition chamber at the lower end of the inclined wall having an opening along the upper part of the stock flow for igniting the stock, an opposed inclined wall having air openings for supporting the stock flow, and a suction chamber below the last named inclined wall for drawing air from the ignited part of the stock through the stock flow.

2. In a sintering machine, an enclosed stock feeding chute, vertically disposed, including a vertical stock guide having a vertical wall and an adjacent horizontal wall, said horizontal wall forming with its adjacent vertical wall a flow retarding pocket at the lower end of the first stock guide, a second vertical stock guide, having a vertical wall and an adjacent horizontal wall, said horizontal wall forming with its adjacent vertical wall a flow retarding pocket at the lower end of the second stock guide, disposed laterally out of vertical alignment with the first stock guide for directing the stock at an angular direction to the vertical flow of the first stock guide, an inclined wall between the pockets for directing the stock flow at an angular direction to the vertical flow in the second stock guide, an ignition chamber at the lower end of the inclined wall having an opening along the upper part of the stock flow for igniting the stock, an opposed inclined wall having air openings for supporting the stock flow, a suction chamber below the last named inclined wall for drawing air from the ignited part of the stock through the stock flow, and a cooling device below the ignition chamber and adjacent to the same, for cooling the ignited stock, and disposed out of the aforesaid air flow.

3. In a sintering machine, an enclosed stock feeding chute, vertically disposed, including a vertical stock guide having a vertical wall and an adjacent horizontal wall, said horizontal wall forming with its adjacent vertical wall a flow retarding pocket at the lower end of the first stock guide, a second vertical stock guide, having a vertical wall and an adjacent horizontal wall, said horizontal wall forming with its adjacent vertical wall a flow retarding pocket at the lower end of the second stock guide, disposed laterally out of vertical alignment with the first stock guide for directing the stock at an angular direction to the vertical flow of the first stock guide, an inclined wall between the pockets for directing the stock flow at an angular direction to the vertical flow in the second stock guide, an ignition chamber at the lower end of the inclined wall having an opening along the upper part of the stock flow for igniting the stock, an opposed inclined wall having air openings for supporting the stock flow, a suction chamber below the last named inclined wall for drawing air from the ignited part of the stock through the stock flow, a sintering pass for the flow of stock having parallel perforated top and bottom walls with closed side walls, inclined to the perpendicular, and a suction chamber on a wall of the sinter pass for drawing air through the stock in the sinter pass through the openings of a wall of the sinter pass, whereby the stock descends by gravity from the chute, passes the ignition chamber and passes through the sinter pass to its discharge at the lower end of the sinter pass in the form of sinter.

4. In a sintering machine, an enclosed stock feeding chute, vertically disposed, including a vertical stock guide having a vertical wall and an adjacent horizontal wall, said horizontal wall

forming with its adjacent vertical wall a flow retarding pocket at the lower end of the first stock guide, a second vertical stock guide, having a vertical wall and an adjacent horizontal wall, said horizontal wall forming with its adjacent vertical wall a flow retarding pocket at the lower end of the second stock guide, disposed laterally out of vertical alignment with the first stock guide for directing the stock at an angular direction to the flow of the first stock guide, a first inclined wall between the pockets for directing the stock flow at an angular direction to the perpendicular in line with the discharge flow in the second stock guide, a second inclined wall extending from the second horizontal wall, downwardly substantially parallel with the first inclined wall, an ignition chamber at the lower end of the first inclined wall having an opening along the upper part of the stock flow for igniting the adjacent surface of the stock, said second inclined wall having air openings, a suction chamber below the last named inclined wall for drawing air from the ignited part of the stock through the stock flow, a sinter pass for the flow of the stock having parallel perforated front and rear walls with closed side walls, said front and rear walls inclined to the perpendicular in a direction opposite to the direction of inclination of the aforesaid first inclined wall, a suction chamber above the upper part of the rear wall of the sinter pass for drawing air through the stock in the sinter pass from the openings of the front wall of the sinter pass, and means at the upper end of the sinter pass and below the ignition chamber, consisting of a pusher, for transposing the ignited surface of the stock from its direction along the first inclined wall adjacent the ignition chamber to a direction along the front wall of the sinter pass, the said inclinations of all of said inclined walls being such as to retard but not to prevent the flow of stock under the action of gravity, whereby the stock descends in mass, passes the ignition chamber and passes through the sinter pass to its discharge at the lower end of the sinter pass in the form of sinter, being propelled in such passage by the action of gravity.

5. In a sintering machine, the combination of a vertically disposed feed chute for stock having spaced front, rear and side walls, and having an open top and an opening at its lower end, with means discharging the stock at an inclination to the perpendicular, an ignition device for igniting the adjacent free upper surface of the stock flowing from said means in a mass discharging from the end of said means flowing along said ignition device, an inclined sinter pass having an open top in communication with said chute discharge means, for receiving the stock passing along the ignition device, said sinter pass having parallel perforated front and rear walls and closing side walls, said front surface of ignited stock mass being unimpeded to flow until it rests on the top of the front sinter pass wall, means for transposing the said front surface of said ignited stock at the top of the front sinter pass wall from a position above the stock as it moves from the ignition device to one below the stock along the front sinter pass wall, said means including a pusher having a pusher surface angularly disposed at an acute angle to the upper inclined surface of the stock as it moves towards said front wall flowing from said ignition device and disposed at an obtuse angle to the front wall of said sinter pass, and means for intermittently operating said pusher, whereby when the pusher

is moved downward in a direction parallel to the front wall of the sinter pass, the ignited surface of the stock flowing from said ignition device is pushed into the lower part of the sinter stock of the sinter pass, and is held down by the stock in the sinter pass to a position in the sinter pass below the stock therein, and when the pusher is moved in the reverse direction ignited stock flowing from the ignition device moves in front of the pusher.

6. In a sintering machine, the combination of a vertically disposed feed chute for stock having spaced front, rear and side walls, and having an open top and an opening at its lower end, with means discharging the stock at an inclination to the perpendicular, an ignition device for igniting the adjacent free upper surface of the stock flowing from said means in a mass discharging from the end of said means flowing along said ignition device, an inclined sinter pass having an open top in communication with said chute discharge means, for receiving the stock passing along the ignition device, said sinter pass having parallel perforated front and rear walls and closing side walls, said front surface of ignited stock mass being unimpeded to flow until it rests on the top of the front sinter pass wall, means for transposing the said front surface of said ignited stock at the top of the front sinter pass wall from a position above the stock as it moves from the ignition device to one below the stock along the front sinter pass wall, said means including a pusher having a pusher surface angularly disposed at an acute angle to the upper inclined surface of the stock as it moves towards said front wall flowing from said ignition device and disposed at an obtuse angle to the front wall of said sinter pass, and means for intermittently operating said pusher, whereby when the pusher is moved downward in a direction parallel to the front wall of the sinter pass, the ignited surface of the stock flowing from said ignition device is pushed into the lower part of the sinter stock of the sinter pass, and is held down by the stock in the sinter pass to a position in the sinter pass below the stock therein, and when the pusher is moved in the reverse direction ignited stock flowing from the ignition device moves in front of the pusher, with an extension of the angular rear wall above the sinter pass into the sinter pass space at the upper end of the rear wall of the sinter pass, this extension forming an acute angle with the rear wall of the sinter pass providing a space free from the direct gravity flow of stock between said extension and the rear wall of the sinter pass, whereby any pressure by the pusher on the stock is relieved and taken up in the said space.

7. In a sintering machine, the combination of a gravity flow sinter pass including a front wall, a parallel rear wall spaced therefrom, and side walls connecting the front and rear walls forming an elongated chute for guiding stock in the mass throughout its cross-section, having an open upper receiving end, and an open lower discharging end, said front wall having an inclination to the perpendicular to retard but not to prevent the descent of the stock by gravity from the open upper receiving end towards the lower discharge end, a feed chute having an elongated upper portion of vertically disposed walls open at the top of said portion to receive the stock and open at the bottom of said portion to discharge the stock, for enclosing stock throughout the cross-section of said portion from said top

to said bottom in vertical flow providing an air choke, said feed chute having a vertically disposed lower portion of substantially vertically disposed stock-enclosing walls, said walls having an opening at their upper end and with a discharge opening at their lower end, below said upper portion and in continuation therewith, to receive the stock discharged from the bottom of said upper portion, said last named lower portion having an inwardly extending horizontal wall in the vertical downward path of the discharge of the upper portion, the lower portion below said horizontal wall being disposed laterally out of vertical alignment with the upper portion for directing the stock flow in a direction in an angular direction to the vertical flow of the upper portion, all portions of the feed chute from its top to its bottom forming a continuous air tight enclosure with the stock therein forming an overall air choke, said feed chute being above the sinter pass receiving end and having the discharge opening of its lower portion in stock communication with the open upper end of the sinter pass and adjacent thereto, a stock igniting device above the free flowing surface of said stock as it discharges from the feed chute into said sinter pass, for igniting the surface of said stock adjacent said device, and means supplying air to the stock in the sinter pass chute for continuing the burning of the stock in the sinter pass during the flow of the stock in the sinter pass chute until the stock in said sinter pass chute

is converted to sinter, the discharge of the sinter being from the lower end of the sinter pass, said sinter acting as an air choke in the lower end of the sinter pass.

8. The structure of claim 7, with sinter breaking roller means at said lower discharging end of the sinter pass for breaking the sinter discharging from the lower end of the sinter pass, and means varying the speed of said sinter breaking means, whereby the movement of the stock in the sinter pass is controlled.

WALTER KELSEY.
